UNITED STATES PATENT OFFICE.

HORACE A. CURETON, OF LOS ANGELES, CALIFORNIA.

RADIATOR.

1,381,618.

Specification of Letters Patent. Patented June 14, 1921.

Application filed February 19, 1918. Serial No. 218,086.

To all whom it may concern:

Be it known that I, HORACE A. CURETON, a citizen of the United States, residing at Los Angeles, in the county of Los Angeles 5 and State of California, have invented a new and useful Radiator, of which the following is a specification.

This invention relates to a radiator and particularly pertains to that class of radiators employed in conjunction with internal combustion engines for cooling the circulating liquid employed in engine cooling systems.

The object of this invention is to provide 15 a radiator of the above character comprising a series of radiator units, each of which units is built up of a series of superposed complementary elements or chambers adapted to be readily removed and replaced.

20 A further object is to provide a radiator so constructed and arranged that the liquid to be cooled may flow rapidly and freely therethrough in large volume without danger of being impeded by collections of sediment, and at the same time be distributed 25 over a large cooling surface.

Other objects will appear hereinafter.

The invention is illustrated in the accompanying drawings, in which:

30 Figure 1 is a view in sectional elevation with parts broken away showing a pair of the radiator units as applied and illustrating the manner of assembling the units.

Fig. 2 is a plan view of one of the radiator 35 units.

Fig. 3 is a view illustrating a modified form of the unit.

Fig. 4 is a view in sectional elevation showing a modified form of the unit.

40 Fig. 5 is a detail section of the element employed in said unit.

Fig. 6 is a plan view corresponding to Fig. 5.

45 Figs. 7 and 8 are plan views illustrating the further modified forms of the radiator elements.

In carrying out the invention a pair of upper and lower horizontally extending manifolds 10 and 11 are employed which 50 communicate with the water circulating system of internal combustion engines in the usual manner and between which manifolds my radiator elements 12 are detachably arranged. These radiator elements are composed of a series of superposed units 13 consisting of substantially flat hollow members

formed with thin sheet metal, top and bottom walls 14 and 15 joined together at their edges by a seam 16; openings 17 and 18 being formed in the top and bottom walls adapted 60 to register with like openings in the walls of the adjacent unit to form a passage extending vertically through the radiator element and forming an open communication between the successive units. The margins of 65 the openings are pressed outwardly from the face of the unit wall to form spacing collars 19 having flat outer faces and tapered side walls so that when the walls of adjacent units are joined they will be spaced apart 70 except at the point of juncture of the collar. Joining of the adjacent units is effected by soldering the collars together. The lowermost unit seats on a plate 20 having an opening through which the lower collar extends, 75 this lower collar being affixed to a union coupling 21 having the usual threaded sleeve 22 adapted to be secured on a threaded nipple on the manifold 11. Secured to the plate 20 is a pair of upwardly extending walls 24 80 and 25 which connect at and extend alongside the edges of the units and connect at their upper ends to a plate 26 attached to the top unit and having an opening through which the upper collar 19 extends. This 85 collar connects with the union coupling 27 having a threaded sleeve 28 adapted to be secured on a threaded nipple 29 on the manifold 10. The walls 24 and 25 are formed with ribs 30 which extend beneath the outer 90 edges of the units and form supports therefor.

In the preferred form of the invention shown in Figs. 1 and 2 the openings 17 and 18 in the walls of the units are oblong and 95 the opening in one wall is arranged at right angles to the opening in the other wall with the centers of the openings in alinement. This forms a vertical passage leading from one manifold to the other through the radiator element. The openings being elongated, their end portions extend beyond the longitudinal edges of each other so that a portion of wall will extend directly opposite the end portions of the openings to provide 105 baffles by which the flow of liquid through the radiator element will be broken up and deflected so as to cause the liquid to circulate throughout the chamber in each unit. The units may be formed rectangular in plan 110 as shown in Fig. 2, or they may have any other desired form of outline, for example,

the units may be shaped in the form of equilateral triangles as shown in Fig. 3, in which event the elongated openings on the opposite walls of the unit will be disposed in diagonal relation to each other.

5 In the form of the invention shown in Figs. 4 to 8 inclusive, the openings in the walls of the units are offset or staggered in relation to each other, which construction 10 necessitates the liquid traveling in a zigzag course from one manifold to the other.

I claim:

1. In a radiator, a series of hollow sheet metal units each of which comprises top and 15 bottom plates secured together at their edges and each of said plates having an opening, spacing flanges surrounding said openings extending outwardly from the plates and forming raised portions adapted to seat on 20 the raised portions of adjacent units, said units being soldered together at their raised portions, plates extending over the upper and lower units, walls secured to said plates extending alongside the units, and shoulders 25 on said walls extending under the opposed edges of said units holding same in spaced relation to each other.

2. In a radiator, a pair of spaced threaded nipples, a series of superposed separable hollow units interposed between said nipples 30 and having open communication with each other, detachable threaded connections between the end units and the nipples, and vertical walls extending alongside the superposed units and engaging the edges thereof 35 for supporting the units in spaced relation to each other.

3. In a radiator, a unit formed of horizontally disposed spaced walls connected together at their edges, said walls each having 40 raised portions surrounding an opening therein, said raised portions having flat end walls forming the margins of the openings adapted to seat on the raised portion of an adjacent unit and to be detachably secured 45 thereto by a soldered joint whereby intermediate units in a series thereof may be removed and replaced without detaching other units of a series and vertical walls arranged 50 alongside the units and engaging the edges thereof for supporting the units in spaced relation to each other.

HORACE A. CURETON.
